AUTOMATIC TRAIN CONTROL

Application filed July 17, 1929. Serial No. 293,341.

This invention relates to a system of railway signalling and particularly to a system in which both track circuit control and central control is employed and more especially to such systems in which the progress of trains is indicated or recorded at a central station.

I have heretofore proposed a system of train control wherein means are provided whereby an operator can instantly change the signals on a section of track for one direction of train movement to the opposite direction if there is no train in the section, the section being divided into a number of blocks so as to facilitate following train movements.

In this invention the signals on any number of sections of track, which are subdivided into several blocks may be changed from a central point such as a dispatcher's office, interlocking tower or way station by an operator, if there is no train in the section. That is an operator having control over a plurality of sections of track may set up the signal protection so as to provide for an east bound movement of trains but if there is no train in the section, he may instantly change the signal protection for the section so as to provide for a west bound movement of trains.

In order that the operator may intelligently govern train movements with the least delay, means are provided to automatically indicate or record the movement of trains at his office so that he has knowledge of the location and progress of all trains under his jurisdiction.

A further object of the invention is to prevent the operator from setting up proceed signals over a section of track for both an east bound and a west bound movement at the same time and to prevent him changing from one direction to the opposite as long as there is a train in the section.

Other objects and advantages will appear as the description of the particular physical embodiment of the invention and desirable modifications thereof selected to illustrate the invention progresses and the novel features will be pointed out in the appended claims.

In describing the invention in detail, ref-

erence is had to the accompanying drawings wherein I have illustrated a preferred physical embodiment of my invention and a desirable modification thereof and wherein like characters of reference designate corresponding parts throughout the several views, and in which:

Fig. 1 is a schematic representation of the apparatus and circuits in the dispatcher's office and along the track; Fig. 2 is a schematic representation of the apparatus and circuits on the locomotive or car; Fig. 3 is a modification of the system delineated by Fig. 1 and shows a schematic representation of part of the apparatus in the dispatcher's office and along the track by which fixed signals are displayed instead of cab signals.

Fig. 1 shows a single track consisting of rails 1 and 2. Rail 1 is electrically continuous. Rail 2 is divided into sections by means of insulating joints, as 3, thus dividing the track into block sections, as A, B, C, D, E, F and G. In blocks B and F are shown sidings, as 4, where trains may meet and pass each other. Since the apparatus and circuits for each single track section between passing sidings are identical, only one complete single track section has been shown in Fig. 1, but the dispatcher's control and the recording of train movements has been shown for three

single track sections, thus, a switch, as 5, in the dispatcher's office, interlocking tower or way station controls the signals for a section west of block B. A switch as 6 controls the signals of the section between blocks B and F; and a switch as 7 controls the signals of a section east of block F. At the clearance point of the sidings insulating joints, as 3, electrically separate the straight portions of the siding from the main track in a manner and for a purpose well known to those skilled in the art.

Each block is provided with a track circuit, a track battery as 8 being located at one end of each block and track relays as a, b, c, d, e, f, and g near the other end of the block, constituting with their connections to the rails, a track circuit well known to those skilled in the art. Track relays a, b, d, e and f control two armatures as 9 and 10 and track relays c

and *g* control three armatures as 9, 10 and 11. When there is no train in the block, the track relay for the block is energized and its armatures through their respective front contacts, 5 control certain signals, and when there is a train in the block, its track relay is de-energized and its armatures will close certain back contacts for the purpose of locking switches 5, 6 and 7, and making a record of train 10 movements, as will be described in more detail hereinafter.

Adjacent to the track are located groups of train control rails as A12 and A13, B12 and B13, C12 and C13, D12 and D13, E12 and E13, F12 and F13 and G12 and G13. Train control rails 12 and 13 are on the right hand side of the center line of the track, looking east, and control east bound movements into a block, and a similar group of train control rails on the opposite side of the track that is on the right hand side of the center line of the track, looking west, control west bound train movements into a block. These west bound train control rails have been designated as A14 and A15, B14 and B15, C14 and C15, D14 and D15, E14 and E15, F14 and F15, and G14 and G15. In each group of train control rails one is the home train control rail and located near the entrance to a new block 30 and the other is a distant train control rail and located approximately the braking distance from the entrance of a new block. Thus train control rail 13 is the home train control rail for an east bound train movement and train control rail 14 is the home train control rail for a west bound movement and train control rail 12 is the distant train control rail for an east bound movement and train control rail 15 is the distant train control rail for a west bound train movement. When east bound train control rails are positively energized, a clear signal is displayed on an east bound locomotive and when train control rails are negatively energized or de-energized a danger signal is displayed on an 45 east bound locomotive. When the west bound train control rails are negatively energized a clear signal is displayed on a west bound locomotive but when these train control rails are positively energized, or de-energized, a danger signal is displayed on a locomotive. The train control rails are positively energized from a battery as 16, preferably located in the dispatcher's office, by a certain position of manually operable switches 5, 6 and 7, and they are negatively energized from a battery as 17 by certain other positions of the manually operable switches, 5, 6 and 7, but if 55 switches 5, 6 and 7 are in a position to display a clear signal for either an east bound or a west bound movement, the train control rails will not be energized with the selected energy if the block ahead is occupied since the circuit 60 from the dispatcher's office is broken through

the corresponding track relay of the occupied block.

I will now describe how a certain group of train control rails may be energized positively, or negatively or de-energized, from the dispatcher's office and since manually operable switch 6 controls the section between blocks A and F representing a complete section between passing sidings I will trace the circuits through switch 6.

When switch 6 is in the position as shown in Fig. 1, making contact with a spring contact as 18 it is in the position to give a clear signal to an east bound locomotive from block A to block E and if there is no train in any one of these blocks, train control rails A12 and A13, B12 and B13, C12 and C13 and D12 and D13 are all positively energized and are thus conditioned to give a clear signal to an east bound locomotive. The train control rails A12 and A13 are energized through the following circuit: from positive pole of battery 16, bus 20, wire 21, contact spring 18, switch 6, shaft 22, wire 23, relay 24, line wire 25, wires 26 and 27, armature 11 of track relay *c*, front contact 30, wire 31, front contact 29, of track relay *b*, armature 10, and wire 32 to train control rails A13 and A12, and thence through a circuit on the locomotive to be described hereinafter to track rail 1 and thence through wires 33 and 34 to negative pole of battery 16. Similarly train control rails B12 and B13 are positively energized through a branch circuit as follows: from positive pole of battery 16, bus 20, wire 21, spring contact 18, switch 6, shaft 22, wire 23, relay 24, wires 25, 26 and 35, armature 10 of track relay *c*, front contact 29, and wire 36, to train control rails B13 and B12, and thence the circuit is completed to negative pole of battery 16, as hereinbefore described. Similarly train control rails C12 and C13 are energized through a branch circuit as follows: from positive pole of battery 16, bus 20, wire 21, wire 22, spring contact 18, switch 6, shaft 22, wire 23, relay 24, line wire 25, wires 37, 38 and 39, armature 10 of track relay *d*, front contact 29, wire 40 to train control rails C13 and C12 and thence the circuit is completed to negative pole of battery 16 as hereinbefore described. Similarly train control rails D12 and D13 are positively energized through a branch circuit as follows: from positive pole of battery 16, bus 20, wire 21, spring contact 18, switch 6, shaft 22, wire 23, relay 24, line wire 25, wires 41 and 43, armature 10 of track relay *e*, front contact 29, wire 44, to train control rails D13 and D12 and thence the circuit is completed to negative pole of battery 16, as hereinbefore described. It will be noted that the circuit to train control rails A12 and A13 is taken through the armatures of both track relays *b* and *c* so that if either of these blocks is occupied, train control rails A12 and A13 will 115

be de-energized and the purpose of this will be described more fully hereinafter. With switch 6 in contact with spring contact 18, train control rails G14 and G15, F14 and F15, D14 and D15 and C14 and C15 will also be positively energized but as will be more fully described hereinafter, a west bound train requires negative energy to obtain a clear signal at a train control rail and will receive a danger signal if passing a positively energized or de-energized train control rail.

When switch 6 is placed in the position opposite to that shown in Fig. 1, so as to make contact with spring contact 19, it is in the position to give a clear signal to a west bound locomotive from block G to block C and if there is no train in any of these blocks, train control rails G14 and G15, F14 and F15, E14 and E15 and D14 and D15 are all negatively energized, thus conditioned to give a clear signal to a west bound locomotive. Train control rails G14 and G15 are negatively energized through the following circuit: from negative pole of battery 17, bus 45, wire 46, spring contact 19, switch 6, shaft 22, wire 23, relay 24, wires 25, 37, 41, 47 and 48, armature 9 of track relay *f*, front contact 28, wire 49, to train control rails G14 and G15 and thence through a circuit on the locomotive to be described hereinafter to track rail 1, and thence through wires 33 and 50 to the positive pole of battery 17, this circuit being traced against the direction of flow. Similarly train control rails F14 and F15 are negatively energized through the following circuits: from negative pole of battery 17, bus 45, wire 46, spring contact 19, switch 6, shaft 22, wire 23, relay 24, wires 25, 37, 41, 42 and 51, armature 9 of track relay *e*, front contact 28, wire 52 to train control rails F14 and F15 and thence through a circuit on the locomotive to be described hereinafter to track rails 1 and thence through wires 33 and 50 to the positive pole of battery 17, the circuit being traced against the direction of flow. Similarly train control rails E14 and E15 are negatively energized through the following circuit: from negative pole of battery 17, bus 45, wire 46, spring contact 19, switch 6, shaft 22, wire 23, relay 24, wires 25, 37, 38 and 53, armature 9 of track relay *d*, front contact 28, wire 54, train control rails E14 and E15 and thence through a circuit on the locomotive to be described hereinafter to track rail 1 and thence through wires 33 and 50 to the positive pole of battery 17, the circuit being traced against the direction of flow. Similarly train control rails D14 and D15 are negatively energized through the following circuit: from negative pole of battery 17, bus 45, wire 46, spring contact 19, switch 6, shaft 22, wire 23, relay 24, wires 25, 26 and 55, armature 9 of track relay *c*, front contact 28, and wire 56, to train control rails D14 and D15 and thence through a circuit

on the locomotive to be described hereinafter to track rail 1 and thence through wires 33 and 50 to the positive pole of battery 17, this circuit being traced against the direction of flow.

When switch 6 is in the vertical position so as not to make contact with spring contacts 18 or 19, both east bound and west bound train control rails are de-energized and thus conditioned to display a danger signal on both an east bound and a west bound locomotive, as will be more fully described hereinafter.

It will thus be seen that the dispatcher may condition the train control rails governing the single track section between passing sidings for an east bound train movement or a west bound train movement or he may condition them to display a danger signal to both east and west bound trains. In addition however to the dispatcher's manual control of the electrical conditions of the train control rails, automatic control is also provided by means of a track circuit. Assuming that there is no train in any of the blocks between B and E, and the dispatcher has set up an east bound movement by placing switch 6 in contact with spring contact 18 and a train receiving a clear signal at train control rail B13 proceeds into block C. As soon as the train has entered block C, the current from track battery 8 of block C is short circuited through the wheels and axles of the train and therefore track relay *c* becomes sufficiently de-energized so that its armatures will drop away from the front contacts. When this occurs train control rails B12 and B13 become de-energized, since the circuit is now broken by armature 10 of track relay *c* dropping away from front contact 29. As soon, however, as the train has left block C and entered block D, track relay *c* again becomes energized, thus again closing the circuit to train control rails B12 and B13 and a second train may proceed eastward with a clear signal. It will therefore be seen that a train as it proceeds over the road automatically protects itself in the rear so that a following train will automatically receive a danger signal when it arrives within braking distance of a train ahead occupying the block ahead. The same automatic rear end protection by means of a track circuit is also provided for west bound movements. For instance, a west bound train entering block E will de-energize track relay *c*, thus breaking the circuit at front contact 28 of track relay *c* and de-energizing west bound train control rails F14 and F15. As soon, however, as this train has left block E, train control rails F14 and F15 are again energized, thus permitting a second train to proceed with a clear signal.

The object of taking the circuit to train control rails A12 and A13 through both track relays *b* and *c* and the circuit through

train control rails E12 and E13 through both track relays *b* and *g* is as follows: If the dispatcher has placed switch 6 in contact with spring contact 18, thus setting up an east bound movement for a train from blocks B to E, and also placed switch 7 in contact with spring contact 19, thus setting up a west bound movement for a train running in the single track section east of block G, the two trains will have to meet and pass each other at the siding in block F. If now the east bound train enters block E at approximately the same time that the west bound train entered block G, each train will automatically receive a danger signal by reason of the track circuit control, before reaching block F and this will give the trains ample distance to slow down or stop until one of the trains has taken the siding. This arrangement is desirable if block F and the siding are relatively short. While this arrangement shows the preferred form it is not absolutely necessary, particularly if block F and its siding is relatively long. The arrangement of taking the circuit to the train control rails through two track relays can also be obviated by placing the distant train control rails F12 and G15 sufficient distance back to give the engineer ample warning to stop for the meet.

The system is so arranged that when the dispatcher has set up an east bound movement from block B to block E by placing switch 6 in contact with spring contact 18, as soon as the train has entered block C after receiving a clear signal at train control rails B13, switch 6 is automatically locked in the position it is in, so that it cannot be moved by the dispatcher and the switch remains locked until the train has passed out of block E. This is accomplished in the following manner: switches 5, 6 and 7 are rotatable on the shaft 22. Secured to this shaft is a disk, as 57. In the periphery of this disk are two notches as 58 and 59. The armature as 60, of relay 24, is hinged at 61. At the other end of armature 60 is a detent, as 62, so positioned that when switch 6 is in contact with spring contact 18, detent 62 will be in alignment with notch 58 and when switch 6 is in contact with spring contact 19, detent 62 will be in alignment with notch 59. Relay 24 when sufficiently energized will attract armature 60 and detent 62, and if in alignment with either notch 58 or 59 will engage one of the notches, thus preventing the switch from being turned from the position it is in as long as relay 24 is energized. When relay 24 is not sufficiently energized a spring as 63 pulls detent 62 out of engagement with disk 57.

When switch 6 is in contact with spring contact 18, relay 24 is energized as long as there is a train in either of blocks C, D or E. When block C is occupied relay 24 is

energized through the following circuit: from battery 16 in the dispatcher's office, bus 20, wire 21, spring contact 18, switch 6, shaft 22, wire 23, relay 24, wires 25, 26 and 27, armature 11 of track relay *c*, back contact 64, wire 65, track rail 1, and thence through wires 33 and 34 to the negative pole of battery 16. When block D is occupied, relay 24 is energized through the following circuit: from positive pole of battery 16, bus 20, wire 21, spring contact 18, switch 6, shaft 22, wire 23, relay 24, wires 25, 37, 38 and 39, armature 10 of track relay *d*, back contact 64, wire 66, to track rail 1, and thence through wires 33 and 34 to negative pole of battery 16. When block E is occupied relay 24 is energized through the following circuit: from positive pole of battery 16, bus 20, wire 21, spring contact 18, switch 6, shaft 22, wire 23, relay 24, wires 25, 37, 41, 42 and 43, armature 10 of track relay *e*, back contact 64, wire 67 to track rail 1, and thence through wires 33 and 34 to negative pole of battery 16. It will thus be seen that as long as an east bound train occupies either blocks C, D or E, detent 62 engages notch 58, thus locking switch 6 in the position it is in.

When switch 6 is in contact with spring contact 19, relay 24 is energized as long as there is a west bound train in blocks E, D or C. When block E is occupied relay 24 is energized through the following circuit: from negative pole of battery 17 in the dispatcher's office, bus 45, wire 46, spring contact 19, switch 6, shaft 22, wire 23, relay 24, wires 25, 37, 41, 42, and 43, armature 10 of track relay *e*, back contact 64, wire 67, to track rail 1, and thence through wires 33 and 50 to positive pole of battery 17. When block D is occupied, relay 24 is energized through the following circuit: from negative pole of battery 17, bus 45, wire 46, spring contact 19, switch 6, shaft 22, wire 23, relay 24, wires 25, 37, 38 and 39, armature 10 of track relay *d*, back contact 64, wire 66, to track rail 1, and thence through wires 33 and 50 to positive pole of battery 17. When block C is occupied relay 24 is energized through the following circuit: from negative pole of battery 17, bus 45, wire 46, spring contact 19, switch 6, shaft 22, wire 23, relay 24, wires 25, 26 and 27, armature 11 of track relay *c*, back contact 64, wires 65, to track rail 1, and thence through wires 33 and 50 to positive pole of battery 17.

It will thus be seen that when the dispatcher has set up an east bound movement from block B to block E and a train has accepted a clear or proceed signal and has entered block C, the dispatcher is unable to change the position of switch 6 until the train has left block E and when the dispatcher has set up a west bound movement from block F to block C and a train has accepted a clear or proceed signal and has entered block D, the dispatcher is unable to change the position of

switch 6 until the train has left block C. In other words, the dispatcher is unable to give a proceed signal to both an east bound and a west bound train at the same time, between two points where trains may pass each other.

It will be noted that track relays *b* and *f* have not been provided with a back contact. This back contact has been omitted in the preferred form so that switches 5, 6 or 7 will be unlocked as soon as a train has left the single track portion of the railway and has entered a siding block as B or F. It is desirable in the preferred form, to give the dispatcher full liberty in placing the switches in the position desired as soon as the train has reached the main track or the siding of block B or F.

I will now describe the apparatus and circuits on the locomotive capable of displaying a clear signal to an east bound train when passing a positively energized train control rail and displaying a clear signal to a west bound train when passing a train control rail which is negatively energized and displaying a danger signal to an east bound train when passing a train control rail which is negatively energized or de-energized and displaying a danger signal to a west bound train when passing a train control rail which is positively energized or de-energized, and also how these signals are continued after the locomotive has passed the train control rail.

In Fig. 2 is shown a signal designated as No. 1, representing a clear signal and a signal designated as No. 2, representing the danger signal. While these devices, No. 1 and No. 2, have been designated signals and are shown as lamps, they may equally well represent an electromagnetic device to which motion is given depending upon whether the circuit is energized or de-energized and such electromagnetic devices may be used for other purposes than, or in addition to the display of signals to the engineer, such as, is well known in the art, the proper control of speed control devices or electropneumatic air valves or both, as is well known to those skilled in the art.

In Fig. 2, is shown contact shoe as 68 so positioned on the locomotive as to make contact with train control rails. The contact shoe is hinged at 69. The train control rails are inclined at the ends so as to form a ramp in the usual manner such as is shown in my prior Patent No. 1,140,623, granted May 25, 1915. When the contact shoe slides along this ramp, the shoe is tilted so as to break contact at 70. This motion of the shoe compresses a spring as 71. When the contact shoe leaves the other end of the train control rail, spring 71 forces the contact shoe to the normal position thus again closing contact shoe to the normal position thus again closing contact 70.

The locomotive also carries a polarized relay as 72, a battery as 73, and a manually operable switch as 74. When relay 72 is

positively energized, its neutral armature 75 makes contact with front contacts 76 and 77 and its polarized armatures as 78, 79, 80 and 81 make contact with their respective contacts as 82, 83, 84 and 85, as shown in Fig. 2. When relay 72 is negatively energized, its neutral armature 75 will make contact with front contacts 76 and 77 and its polarized armatures 78, 79, 80 and 81 will assume a position opposite to that shown in Fig. 2, and make contact with their respective contacts 86, 87, 88, and 89. When polarized relay 72 is de-energized its neutral armature 75 will drop away from front contacts 76 and 77 and will make contact with back contact 90. Switch 74 is hinged at 91 and when a locomotive is conditioned for an east bound movement, switch 74 is placed so as to make contact with the terminal, as 92. When the locomotive is conditioned for a west bound movement switch 74 is positioned so as to make contact with the terminal 93.

When the contact shoe 68 is passing, say, train control rail B13, and the train control rail is positively energized, current is supplied to polarized relay 72 from battery 16 in the dispatcher's office through the following circuit:—from positive pole of battery 16, bus 20, wire 21, spring contact 18, switch 6, shaft 22, wire 23, relay 24, wires 25, 26 and 35, armature 10 of track relay *c*, front contact 29, wire 36 to train control rail B13, contact shoe 68, wire 94, polarized relay 72, wires 95, 96, 97 and 98, resistance 99, wire 100, axle 101, wheel 102 to track rail 1 and thence through wires 33 and 34 to the negative pole of battery 16. With polarized relay 72 positively energized its armatures will assume the position shown in Fig. 2. Assuming now that switch 74 is in contact with terminal 92 and in the proper position for an east bound train movement, a circuit through signal lamp No. 1, the clear signal is closed as follows:—from positive pole of battery 73, wire 103, contact 84, polarized armature 80, wire 104, neutral armature 75, front contact 76, wire 105, hinge 91, switch 74, terminal 92, wire 106, polarized armature 79, contact 83, wires 107 and 108, signal No. 1, wires 109, 96 and 110, polarized armature 81, contact 85, wires 111 and 112, to the negative pole of battery 73. When the contact shoe 68 leaves the other end of the positively energized train control rail, contact 70 is again closed and a stick circuit is established through polarized relay 72 as follows:—from positive pole of battery 73, wire 103, contact 84, polarized armature 80, wire 104, neutral armature 75, front contact 77, wire 113, contact 70, shoe 68, wire 24, polarized relay 72, wires 95 and 110, polarized armature 81, contact 85, and wires 111 and 112 to the negative pole of battery 73. Thus signal No. 1 is continued after contact shoe 68 has left the train control rail.

Assuming now that train control rail B13 is negatively energized by reason of switch 6 being in contact with spring contact 19, then when an east bound train is passing this rail, 5 polarized relay 72 will be negatively energized through a circuit as follows:—from negative pole of battery 17 in the dispatcher's office, bus 45, wire 46, spring contact 19, switch 6, shaft 22, wire 23, relay 24, wires 25, 10 26 and 35, armature 10 of track relay *c*, front contact 29, wire 36, train control rail B13, contact shoe 68, wire 94, polarized relay 72, wires 95, 96, 97 and 98, resistance 99, wire 100, axle 101, wheel 102, track rail 1, and thence 15 through wires 33 and 50 to positive pole of battery 17. With polarized relay 72 thus negatively energized its polarized armatures will assume the right hand position opposite to that shown in Fig. 2 and assuming that 20 switch 74 is still in contact with terminal 92, normal for an east bound movement, a circuit is closed through signal No. 2, as follows:—from positive pole of battery 73, wire 103, contact 89, polarized armature 81, wires 110, 96, 97, 114, signal No. 2, wires 115 and 25 116, contact 87, polarized armature 79, wire 106, terminal 92, switch 74, hinge 91, wire 105, front contact 76, armature 75, wire 104, polarized armature 80, contact 88, and wire 30 112, to the negative pole of battery 73. When the contact shoe 68 leaves the other end of a negatively energized train control rail contact 70 is closed and a stick circuit is established through polarized relay 72 as follows: 35 from positive pole of battery 73, wire 103, contact 89, polarized armature 81, wires 110 and 95, polarized relay 72, wire 94, contact shoe 68, contact 70, wire 113, front contact 77, armature 75, wire 104, polarized armature 80, 40 contact 88, and wire 112 to negative pole of battery 73. Thus signal No. 2 is continued after contact shoe 68 has left the train control rail.

Assuming now that the train control rail 45 B13 is de-energized by reason of switch 6 being open, that is making neither contact with spring contacts 18 or 19, then, when an east bound train is passing this rail, polarized relay 72 first of all will be de-energized by reason of the stick circuit hereinbefore described 50 being broken at contact 70, when contact shoe 68 slides upon the de-energized train control rail. Since there is no energy from the dispatcher's office polarized relay 72 will remain 55 de-energized and its neutral armature 75 will make contact with back contact 90. Under these conditions a circuit is closed through signal No. 2, the danger signal, as follows: from positive pole of battery 73, wire 103, contact 84, polarized armature 80, wire 104, armature 75, back contact 90, wires 117 and 115, signal No. 2, and wires 114, 97, 96, and 110, polarized armature 81, contact 85, 60 and wires 111 and 112 to negative pole of battery 73. If the train proceeds under these 65

conditions and contact shoe 68 leaves the other end of the train control rail, signal No. 2 will be continued until a positively energized train control rail is reached. After contact shoe 68 leaves the train control rail, 70 contact 70 is again closed but the stick circuit hereinbefore described is now open at front contact 77, and polarized relay 72 will remain de-energized.

It will thus be seen that when switch 74 is 75 in contact with terminal 92 which is the normal position for an east bound train movement when the locomotive is passing a positively energized train control rail, No. 1, the clear signal is displayed, and this signal is 80 continued until the next train control rail is reached, and when the east bound train is passing the negatively energized train control rail, signal No. 2, the danger signal, is 85 displayed and this signal is continued until the next train control rail is reached, and when the east bound train is passing the de-energized train control rail, signal No. 2, the danger signal, will also be displayed and this 90 signal will be continued until the next train control rail is reached. The resistance 99 is inserted in the cab circuit for a purpose which will be explained more fully hereinafter.

Assuming now that the single track section from F to C is set up for a west bound movement, by reason of switch 6 being in contact with spring contact 19, and a west bound train is approaching train control rail F14, switch 74 on a west bound locomotive is in contact with terminal 93, which is the proper position for a west bound movement, when the locomotive is passing train control rail F14, polarized relay 72 will be negatively energized through the following circuit: from positive pole of battery 17 in the dispatcher's office, wires 50 and 33 to track rail 1 and thence wheel 102, axle 101, wire 100, resistance 99, wires 98, 97, 96 and 95, polarized relay 72, wire 94, contact shoe 68, train control rail F14, wire 52, front contact 28, 100 armature 9 of track relay *c*, wires 51, 42, 41, 37 and 25, relay 24, wire 23, shaft 22, switch 6, spring contact 19, wires 46 and 45, to negative pole of battery 17.

With polarized relay negatively energized, 105 its polarized armatures will assume the right hand position opposite to that shown in Fig. 2, and a circuit is closed through signal No. 1 as follows: from positive pole of battery 73, wire 103, contact 89, polarized armature 81, wires 110, 96 and 109, signal No. 1, wires 108 and 118, contact 86, polarized armature 78, wire 119, terminal 93, switch 74, hinge 91, wire 105, front contact 76, armature 75, wire 104, polarized armature 80, contact 88 and 112, to negative pole of battery 73. As the contact shoe 68 leaves the other end of the train control rail, signal No. 1 is continued since the stick circuit hereinbefore described is again established.

Assuming now that the train control rail F14 is positively energized by reason of switch 6 being in contact with spring contact 18, switch 74 is still in contact with contact 93, which is normal for a west bound movement. Under these conditions when a west bound train passes a train control rail F14, polarized relay 72 will be positively energized and a circuit will be established through signal No. 2 as follows:—from positive pole of battery 73, wire 103, contact 84, polarized armature 80, wire 104, armature 75, front contact 76, wire 105, hinge 91, switch 74, terminal 93, wire 119, polarized armature 78, contact 82, wires 116, and 115, signal No. 2, wires 114, 97, 96 and 110, polarized armature 81, contact 85, and wires 111 and 112, to negative pole of battery 73. When the contact shoe 68 leaves the other end of the train control rail, signal No. 2 is continued since the stick circuit hereinbefore described is again established.

If a west bound train is passing train control rail F14, which is de-energized by reason of switch 6 being open or by reason of block E being occupied by a train, polarized relay 72 becomes de-energized and a circuit is established through signal No. 2, as follows: from positive pole of battery 73, wire 103, contact 84, polarized armature 80, wire 104, armature 75, back contact 90, wires 117 and 115, signal No. 2, and wires 114, 97, 96 and 110, polarized armature 81, contact 85, wires 111 and 112, to negative pole of battery 73. As the contact shoe 68 leaves the other end of the de-energized train control rail, signal No. 2 is continued, because while the contact 70 is now closed, the stick circuit is now open at front contact 77 and therefore the polarized relay will continue to be de-energized.

Resistance 99 is placed in the cab circuit for the following purpose: when there is a train in blocks C, D or E, current is flowing through relay 24 in the dispatcher's office thus locking switch 6 in the position it is in as hereinbefore described. When the contact shoe 68 on the locomotive is passing an energized train control rail, current is also flowing through relay 24, but by reason of the combined resistance of polarized relay 72 and resistance 99 there is not sufficient current flowing through relay 24 to attract its armature 60 against the tension of spring 63, therefore a train passing a train control will not lock switch 6. For instance, it is desirable when a train is in block B, that the switches at the dispatcher's office governing the adjacent stretches of track be unlocked and it is possible that a contact shoe on the locomotive may be in contact with either train control rails B12 or B13 and this would lock the switches if the current flow is not reduced as arranged by the introduction of the necessary resistance in the cab circuit.

I will now describe the means by which

an indication or a record is made in the dispatcher's office of the movement of trains. In the dispatcher's office is a suitably mounted record sheet as 120 driven by a roller as 121, which in turn is driven by a shaft as 122. Shaft 122 receives motion through ratchet wheel as 123. A pawl as 124 is pivotally connected to armature 125 of electromagnet 126, the armature being hinged at 127. When electromagnet 126 is periodically energized motion is given to ratchet wheel 123 by a pawl 124. A spring as 128 normally pulls armature 125 and pawl 124 to the right, when electromagnet 126 is not energized. Electromagnet 126 is connected by wire 129 to a make and break device as 130 which make and break device is periodically operated by a clock as 131. This may well be of the form shown in my prior Patent No. 1,203,146, granted October 21, 1916. When the make and break device is closed the electromagnet 126 is energized through the following circuit:—from battery 132, wires 133 and 134, electromagnet 126, wire 129, make and break device 130, wire 135 and 136, to the other side of battery 132. The make and break device 130 is operated say every five seconds so as to give a slow and uniform movement to record sheet 120 through ratchet wheel 123 and pawl 124.

The record sheet 120 is transversely divided into sections as 137, 138 and 139, each section representing a section of single track between sidings or other points where trains may pass each other. Longitudinally the record sheet is divided into time lines such as 1 a. m., each one of the lines representing a one minute interval. It will thus be seen that longitudinally the record sheet assumes a constantly changing position during the twenty-four hours of the day.

Adjacent to the record sheet are located perforating magnets as 140 and 141, two for each section of single track. These perforating magnets control armatures 142. Pivotally attached to armature 142 are perforating needles 143, so positioned adjacent to the record sheet that when a perforating magnet is energized, a perforation is made in the record sheet. As hereinbefore stated, whenever blocks C, D, or E are occupied by a train, relay 24 is energized.

Perforating magnet 140 records east bound train movements through blocks C, D, and E, and perforating magnet 141 records west bound train movements through blocks E, D and C. As heretofore described, when blocks C, D and E are occupied by either an east bound or a west bound train, relay 24 is energized and its armature 60 is in the energized position. Attached to armature 60 but insulated therefrom is a contact plate as 144 and when armature 60 is in the energized position this contact plate makes contact with contacts 145 and 146, thus closing the circuit

through the perforating magnet at this point. Also attached to switch 6 are metallic wedges 147 and 150 but insulated therefrom. When switch 6 is set up for an east bound train movement, thus making contact with spring contact 18, metallic wedge 147 makes electrical contact with spring contacts 148 and 149 thus closing the circuit through perforating magnet 140 at this point. The circuit through perforating magnet 140 is as follows: from battery 132, wires 133 and 151, contact 152, metallic plate 153, contact 154, bus 155, wires 156 and 157, perforating magnet 140, wire 158, spring contact 148, metallic wedge 147, spring contact 149, wire 159, contact 145, metallic plate 144, contact 146, wires 160 and 136 to battery 132.

When switch 6 is set up for a west bound train movement thus making contact with spring contact 19, metallic wedge 150 makes electrical contact with spring contacts 161 and 162, thus closing the circuit through perforating magnet 141 at this point. The circuit through perforating magnet 141 is as follows: from battery 132, wires 133 and 151, contact 152, metallic plate 153, contact 154, bus 155, wires 163 and 164, perforating magnet 141, wire 165, spring contact 161, metallic wedge 150, spring contact 162, wires 166 and 159, contact 145, metallic plate 144, contact 146, wires 160 and 136 to other side of battery 132.

It will be noted that the circuits through the perforating magnets are taken through a circuit breaking device as 153, so that these circuits when completed through metallic plate 144 and metallic wedges attached to switch 6 are periodically made and broken. This circuit breaking device operates as follows: metallic contact plate 153 is attached to armature 125 but insulated therefrom. Every time electromagnet 126 is energized, which as hereinbefore stated is say every five seconds, the contacts 152 and 154 are closed through the metallic plate 153. When magnet 126 is deenergized, armature 125 is pulled to the right by spring 128 and the circuit through the perforating magnet is broken. By reason of this periodic breaking of the circuit by the make and break device 130, a continuous perforation is made on the record sheet as long as a section of single track consisting of blocks C, D and E is occupied. Thus when an east bound train leaves block B, perforating magnet 140 will start to perforate in section 138 of the record sheet as soon as the train has entered block C and will continue to perforate until the train has left block E, thus recording the exact time when a train entered the single track section and also giving the length of time the train remained in the single track section. Similarly, a west bound train will record its movement through perforating magnet 141. A dispatcher having a number of track sections

under his control thus knows what progress the trains are making on his division and can direct the train movements by the proper position of the manually operable switches with the greatest dispatch. For instance by reason of the accurate knowledge of the location of trains on his division, he decides that block B is the most suitable place for an east bound train to pass a west bound train. Under these conditions switch 5 will be placed in the east bound position thus making contact with spring contact 18. This will permit the east bound train to proceed with a clear signal up to the distant train control rail A12 at which point the clear signal would change to danger. Switch 6 would be in the west bound position thus making contact with spring contact 19 and the west bound train would proceed with a clear signal until train control rail C15 is reached. This rail being energized with positive energy the clear signal would be changed to danger and the trains would thus be advised to prepare to meet a train. While an east bound train is traveling towards block B, perforating magnet 140 in the section 139 of the record sheet would continue to perforate but this perforation will automatically cease as soon as the east bound train has left block A and entered block B or the siding at block B. Thus the dispatcher would be fully advised of the arrival of the east bound train at B. Similarly the west bound train would make a record of its progress through perforating magnet 141 in section 138 in the record sheet and perforating magnet 141 will continue to perforate as long as the train is in either blocks E, D, or C. As soon, however, as the west bound train has cleared block C, perforating magnet 141 will cease to perforate, and thus the dispatcher is advised that the west bound train has arrived at B. With this knowledge the dispatcher can intelligently change the position of his switches so as to facilitate the movement of trains with the greatest dispatch.

The modification shown in Fig. 3 is identical in so far as circuits and indicating or recording means are concerned as shown and described in Fig. 1 and the difference consists in substituted fixed signals for the train control rail necessary for cab signals. The several blocks, track batteries and track relays and track relay armatures are identical as are also the circuits from the batteries 16 and 17 in the dispatcher's office through the several positions of switches 5, 6 and 7 and the armatures of track relays, but instead of two train control rails being shown for each direction for each block, polarized relays as 167 and 168 are substituted for the control of fixed signals. Polarized relays 167 control fixed signals for east bound train movements and polarized relays 168 control fixed signals for west bound movements.

The polarized relays may control both home and distant signals in a manner well known to those skilled in the art. I will trace the circuits from the dispatcher's office 5 through polarized relay 167 which controls the signals for an east bound movement into block E and also the circuit through polarized relay 168 which controls the signals for a west bound movement into block D. The 10 circuit through polarized relay 167 is as follows: from positive pole of battery 16 in the dispatcher's office, bus 20, wire 21, spring contact 18, switch 6, shaft 22, wire 23, relay 24, wires 25, 37, 41, 42 and 43, armature 10, 15 of track relay e, front contact 29, wire 44, resistance 169, wire 170, polarized relay 167, wire 171, to track rail 1 and thence through wires 33, and 34 to the negative pole of battery 16. With switch 6 in contact with spring 20 contact 18 thus set up for an east bound movement, polarized relays 167 governing the east bound movement of trains into blocks C, D and E are all positively energized, thus closing the circuit through their 25 respective east bound clear signals.

When switch 6 is in contact with spring contact 19, thus set up for west bound train movements, the circuit through polarized relay 168 controlling the west bound signals into block D is as follows: from positive pole 30 of battery 17 in the dispatcher's office, wires 50 and 33 to track rail 1 and thence through track rail 1, wire 172, polarized relay 168, wire 173, resistance 174, wire 54, front contact 28, armature 9 of track relay d, wires 35 53, 33, 37 and 25, relay 24, wire 23, shaft 22, switch 6, spring contact 19, wire 46, bus 45, to negative pole of battery 17.

With current flowing in this circuit, polarized relay 168 will be negatively energized 40 thus displaying a clear signal for a west bound train entering block D, and similarly all of the polarized relays 168, governing the signals for the west bound movement of trains into blocks F, E and C are also negatively energized.

The detail circuits controlled by relay 167 governing the east bound signals from block F to block G and the detail circuits controlled 50 by relay 168 governing the west bound signals from block G to block F are shown opposite block F of Figure 3.

When east bound relay 167 is positively energized, its neutral armature 175 makes contact with front contact 176 and its polarized armature 177 will be in the position shown in Fig. 3, and make contact with contact 178. Under these conditions a circuit is 55 established through signal H, the clear signal for an east bound movement, as follows: from battery 179, properly housed along the track, wire 180, armature 175, front contact 176, wire 181, polarized armature 177, contact 178, wire 181, signal H, wires 182, and 183 to the

opposite side of battery 179. When east bound relay 167 is negatively energized its neutral armature 175 makes contact with front contact 176 and its polarized armature 177 will now be in the position opposite to that shown in Fig. 3, and make contact with contact 184. Under these conditions a circuit is established through signal J, the danger signal, as follows: from battery 179, wire 180, 70 armature 175, front contact 176, wire 181, polarized armature 177, contact 184, wire 185, signal J, and wires 186 and 183 to opposite side of battery 179. When east bound relay 167 is de-energized, its neutral armature 175 makes contact with back contact 187 and a circuit is established through signal J, the danger signal, as follows: from battery 179, wire 180, armature 175, back contact 187, wires 188 and 185, signal J, and wires 186 75 and 183 to other side of battery 179.

When west bound relay 168 is negatively energized, its neutral armature 189 makes contact with front contact 190 and its polarized armature 191 will be in the position 80 shown in Fig. 3, and make contact with contact 192. Under these conditions a circuit is established through signal K, the clear signal from a west bound movement, as follows: from battery 193, wire 194, armature 189, 85 front contact 190, wire 195, polarized armature 191, contact 192, wire 196, signal K, wires 197 and 198 to opposite side of battery 193. When west bound relay 168 is positively energized, its neutral armature 189 makes contact with front contact 190 and its polarized armature 191 will be in the position opposite to that in Fig. 3, and make contact with contact 199. A circuit is established through 90 west bound signal L as follows: from battery 193, wire 194, armature 189, front contact 190, wire 195, polarized armature 191, contact 199, wire 200, signal L, wires 201 and 198 to opposite pole of battery 193. When west bound relay 168 is deenergized, its neutral armature 189, makes contact with back contact 202, and a circuit is established 100 through signal L, the danger signal, as follows: from battery 193, wire 194, armature 189, back contact 202, wires 203, and 200, signal L, and wires 201 and 188 to the other side of battery 193.

Since the circuits from the dispatcher's office through polarized relays 167 and 168 are taken through the track relay of the 105 block ahead, it is obvious that these relays will become deenergized resulting in the display of a danger signal, if the block ahead is occupied by a train as hereinbefore described.

Since it is obvious that relays 167 and 168 110 for other blocks operate in the same manner, it is thought not necessary to describe their operation in further detail. Resistance 169 is inserted between front contact 29 and polarized relay 167 for the same purpose as 115

120 125 130 135

resistance 99 is inserted in the cab circuit, that is to reduce the flow of current through relay 24 in the dispatcher's office so that its armature 60 is not attracted to lock switch 6 unless the armature of a track relay closes a back contact 64, in which case a shunt circuit is established cutting out resistance 169 or 174 thereby increasing the flow of current so as to attract armature 60 of relay 24 and lock the switch in the position it is in.

10 The invention provides a simple and inexpensive system of signalling for a railway where a track is used for both directions of traffic. It is particularly adaptable for single track lines, but it is equally adapted for 15 two or more track lines where it is desirable to use a certain track normally for one direction but at times operate trains with dispatch and safety in the opposite direction.

20 While in the preferred form of my invention I have shown recording means to give the dispatcher knowledge of the location and progress of trains, I do not wish to be restricted to the recording means shown. Any 25 means automatically indicating at the dispatcher's office the location and progress of trains may be considered an equivalent within the scope of my invention. For instance, the perforating magnets 140 and 141 may be 30 indication lamps which are lighted when their respective circuits are closed; thus visibly indicating the location and progress of trains. Or the perforating magnets 140 and 141 may be any form of electrical translating 35 devices which indicate when the circuits through them are closed; thus the position of armature 142 in itself may be a visible indication to the dispatcher of the location and progress of trains.

40 Although I have particularly described one of the physical embodiments of my invention and illustrated the same, nevertheless, I desire to have it understood that the particular form illustrated is merely illustrative, 45 and does not exhaust the possible physical embodiment of means underlying the principle of my invention.

What is claimed is:

1. A system of train control comprising a 50 trackway divided into sections, each section being divided into blocks, sidings between the ends of the sections, train control means adjacent each block for each direction of train movement, a central station, a plurality 55 of currents of different kinds at the central station, circuits leading from the central station to said train control means, a switch selectively operable to energize the train control means for one direction of train movement with one of said currents at the central 60 office to indicate proceed, and also selectively operable to energize the train control means for the opposite direction of train movement 65 with another of said currents to indicate pro-

ceed, track circuits for each block, said track circuits controlling said currents, a locking circuit for the switch to prevent a change in position thereof when a train is in certain blocks of the section, said locking circuit having a part in common with the circuit leading from the central office, said locking circuit being controlled by the track relays of those blocks remote from the sidings but released when the train is in an end block for the section adjacent the siding, whereby a change in signals may not be effected while a train is in the mid portion of a section but may be effected when the train approaches one end of said section.

2. A system of train control comprising a trackway divided into sections, each section being divided into blocks, sidings between the adjacent ends of sections, train control means for either direction of movement over the trackway, track circuits for each block, a central office, a plurality of sources of currents of different kinds at the central office, a switch at the central office for selectively connecting one of said currents to the train control means and another of said currents to said train control means to indicate proceed for one direction and stop for the opposite direction, said currents being controlled by said track circuits to provide rear end protection for a train moving through the section, normally inoperative locking means for said switch, and means including the track relays of certain blocks of the section for causing an operation of said locking means only when a train is in those blocks remote from one end of the siding and said section.

3. A system of train control comprising a trackway divided into sections, each section being divided into blocks, sidings between the sections, track circuits for each block, a central office, a circuit selecting switch therein, a plurality of currents of different kinds at the central office, means along the trackway for either direction of train movement for controlling the movement of a train, circuits from the central office to said train control means, said circuits, when supplied with one of said currents, conditioning the train control means for one direction of operation to indicate proceed, and when supplied with another of said currents, conditioning the train control means for the opposite direction of operation to indicate proceed, devices at the central office for indicating the presence of a train and its direction along the trackway, said devices being concurrently controlled by the selection of current and the presence of a train along the trackway through operation of said track circuits, and a locking circuit for said switch operable by the presence of a train in those blocks remote from one end of said section, said locking

circuit having a part in common with the track relays of those blocks remote from one end of the sidings and sections, whereby the presence of a train at a siding is indicated at the central office and the train control currents therefor may be selected.
